UNITED STATES PATENT OFFICE

137,472

DESIGN FOR A SINGLE-BLADE PROPELLER

Henry Birsh, New York, N. Y.

Application July 19, 1943, Serial No. 110,697

Term of patent 14 years

To all whom it may concern:

Be it known that I, Henry Birsh, a citizen of the United States, residing at New York city, in the county and State of New York, have invented a new, original, and ornamental Design for a Single-Blade Propeller, of which the following is a specification, reference being had to the accompanying drawing, forming part thereof.

Figure 1 is a front elevational view of a single-blade propeller embodying my new design.

Figure 2 is a rear elevational view, and;

Figure 3 is an edge view thereof.

I claim:

The ornamental design for a single-blade propeller, as shown.

HENRY BIRSH.
